ELECTRIC GRASS SHEAR

Robert J. De Brey, Edina, Minn., assignor to Fingerhut Corporation, Minnetonka, Minn.

Filed Oct. 20, 1972, Ser. No. 299,623

Term of patent 14 years

Int. Cl. D8—03

U.S. CL. D8—8

FIG. 1 is a left side exploded perspective view of an electric grass shear, showing my new design;

FIG. 2 is a right side elevational view thereof;

FIG. 3 is a front elevational view thereof;

FIG. 4 is a rear elevational view thereof;

FIG. 5 is a top plan view thereof with the handle shaft member broken away for ease of illustration;

FIG. 6 is a bottom plan view thereof.

I claim:

The ornamental design for an electric grass shear, as shown and described.
